UNITED STATES PATENT OFFICE.

CHARLES A. GILBERT, OF LA PORTE, INDIANA, ASSIGNOR, BY MESNE ASSIGNMENTS,
TO LYON & HEALY, INC., OF CHICAGO, ILLINOIS, A CORPORATION OF ILLINOIS.

SAXOPHONE OCTAVE KEY.

Application filed March 4, 1927. Serial No. 172,597.

This invention relates to improvements in upper octave hole closing and key devices for saxophones and the like, and has for its principal object to provide an improved construction for devices of the class described, wherein the action of the upper octave hole cover and its associated key is rendered positive so as to eliminate the natural tendency of the cover to rebound or flutter when it closes.

My invention is especially applicable to the mechanism for operating the upper octave hole of the saxophone. This hole is placed at the extreme upper end of the instrument, just below the mouthpiece. Heretofore, it has been usually controlled by a cover mounted on a relatively long lever having a spring connected therewith for closing the cover. Said lever is manipulated at the far end thereof, which end extends forwardly and then downwardly along the upper curved portion of the instrument body, and usually is provided with a ring attached to the lower end and surrounding the tube adjacent the other keys, so as to be readily depressed. Accordingly, this control lever is relatively long and massive, and is therefore inclined to be slow and uncertain in action, and especially has a tendency to bounce or flutter when the cover is permitted to strike the hole under pressure of the spring.

My invention consists in providing an improved operating means including a plurality of coacting levers, as will now be described in connection with the accompanying drawing, in which

Figure 1 is a view in perspective of a portion of a saxophone constructed in accordance with my invention.

Figure 2 is an enlarged detail view of the valve mechanism.

Referring to details shown in the drawings, 10 indicates the upper body portion of a saxophone with an octave hole 11 formed therein. A cover 12 of the usual type is provided for the hole, said cover being mounted on a relatively short lever, 13, pivoted at 14 between supports 15, 15. A spring 16 is connected with the lever 13 and tending to close the same, in the form shown said spring being of the flat leaf type, fixed at one end on the lever 13 and having the other end projecting into engagement with a flat bearing surface

16^a on the tube surface and arranged to slide therealong, but tending to maintain the lever 55 in closed position.

A second lever 17, much longer than the first-named lever 13, is pivotally mounted intermediate its ends at 18 on supports 19, preferably arranged so as to swing in substantially the same vertical plane as the shorter lever 13 and with its upper end movably connected to said shorter lever adjacent its free end. In the form shown, the movable connection consists of a pin 20 carried on the end of lever 60 17, and having loose-fitting engagement in an enlarged hole 21 formed in the top of the cover 12. This loose-fitting connection of the parts permits freedom of pivotal movement of the two levers in spite of the difference in the length of their respective lever arms. It is manifest that the ends of the levers may be loosely connected to operate the cover in many ways differing from the specific form shown.

The lower end of the longer lever 17 constitutes the operating key for the mechanism, and for this purpose may be provided with a ring 22, surrounding the tube 10 and operated through a lever (not shown) on the underside of the tube in the same manner as heretofore used with single key levers of the usual type.

A double lever key mechanism constructed as above described, is manipulated in the 85 same manner as before, but provides a more positive action owing to the peculiar construction thereof. The closing spring 16 is effective directly upon the shorter lever 13 at a point immediately adjacent the hole cover 90 12, and the provision of the two cooperating levers of different lengths practically eliminates the tendency to flutter or bounce, which is so marked in the case of the single long control lever as heretofore used at this point. 95 As a result of the positive key action described, the instrument can be played with much more rapidity and ease than formerly without danger of spoiling the tone due to sluggish action or fluttering of the octave 100 hole cover.

While I have illustrated and described the particular embodiment of my invention, it will be understood that I do not wish to be limited to the exact construction shown and 105 described, but that various changes and mod-

ifications may be made without departing from the spirit and scope of my invention as expressed in the following claims.

I claim:

- 5 1. In a device of the character described, an instrument body having an upper octave-hole, a cover for said hole, means for operating said cover including two levers of different effective lengths and connecting means for said levers permitting limited relative movement therebetween.
- 10 2. In a device of the character described, an instrument body having an upper octave-hole, a cover for said hole, means for operating said cover including two levers of different effective lengths and arranged to swing in substantially the same vertical plane and connecting means for said levers permitting limited relative movement therebetween.
- 15 3. In a device of the character described, an instrument body having an upper octave-hole, a cover for said hole, means for operating said cover including two levers of different effective lengths, connecting means for said levers permitting limited relative movement therebetween, and spring tension means effective on the shorter of said levers.
- 20 4. In a device of the character described, an instrument body having an upper octave-

hole, a cover for said hole, means for operating said cover including two levers of different effective lengths and arranged to swing in substantially the same vertical plane, connecting means for said levers permitting limited relative movement therebetween, and spring tension means effective on the shorter of said levers.

5. In a device of the character described, an instrument body having an upper octave-hole, a cover for said hole, a relatively short lever, spring tension means effective through said short lever and tending to close said cover, and a longer, manually controllable lever operatively connected with said cover for raising the same.

6. In a device of the character described, an instrument body having an upper octave-hole, a cover for said hole, a relatively short lever, spring tension means effective through said short lever and tending to close said cover, and a longer, manually controllable lever, arranged to swing in substantially the same vertical plane as said shorter lever, and operatively connected with said cover for raising the same.

Signed at La Porte, Ind., this 28th day of February, 1927.

CHARLES A. GILBERT.
